MESSAGE TRANSMITTING SYSTEM

August D. Elzen, Rockville Centre, N. Y., assignor
to News Projection Corporation, New York,
N. Y., a corporation of New York

Application September 1, 1933, Serial No. 687,811
Renewed October 27, 1937

26 Claims. (Cl. 178—4)

This invention relates to message transmitting systems and more particularly to an improved system for translating a printed message into electric frequencies to be transmitted to a remote station, there to be retranslated into a printed message.

Among the objects of the present invention, it is aimed to provide an improved system for translating a printed message into electric frequencies and transmitting such electric frequencies to a remote station there to be reconverted or retranslated into a printed message.

It is still another object of the present invention to provide an improved system for translating a printed message into alternating or pulsating currents and transmitting such currents to a remote station there to be reconverted or retranslated into a printed message.

It is still another object of the present invention to provide an improved message transmitting system whereby a printed message can be translated into inaudible frequencies and such frequencies transmitted across a telephone line or the like without interfering with the use of the line for ordinary conversation and the like and retranslating such inaudible frequencies at the receiving station into a printed message or a pictorial reproduction of the message.

These and other features, capabilities and advantages of the invention will appear from the subjoined detail description of specific embodiments thereof illustrated in the accompanying drawings in which

Figure 1 is a side elevation more or less diagrammatically showing a sending station made according to the present invention;

Fig. 2 is an enlarged fragmental detail end view of a portion of the sending station illustrated in Fig. 1;

Fig. 3 is an enlarged fragmental plan of the detail illustrated in Fig. 2;

Fig. 4 is a side elevation more or less diagrammatically showing a receiving station made according to the present invention;

Fig. 5 is an enlarged fragmental side elevation of a portion of the receiving station illustrated in Fig. 4;

Fig. 5a is a detail of a portion of the mechanism shown in Fig. 5;

Fig. 6 is an enlarged plan more or less diagrammatically showing a portion of the receiving station illustrated in Fig. 4;

Fig. 7 is an enlarged fragmental plan of a portion of the tape in its position relative to the sending station illustrated in Fig. 1;

Fig. 8 is an enlarged fragmental end elevation of the tape showing its position relative to the sending station illustrated in Fig. 1;

Fig. 9 is a fragmental detail on the line 9—9 of Fig. 8; and

Fig. 10 is a fragmental plan view of a portion of tape usable with the present invention having a single row of printed matter.

In the embodiment illustrated in Fig. 1, there is illustrated a ticker 1 of the high speed type 10 extensively used today in which the tape feed rollers 2 and 3 have been anchored against operation so that the tape 4 may be continually drawn through the ticker at a uniform rate of speed, as for instance by the tape pulling roller 5. The tape 4 in the present instance is held in frictional engagement with the pulling roller 5 by the spring pressed roller 6. The tape puller 5 in turn is drivingly connected to the motor 7 and the shaft of the puller 5 is in turn drivingly connected to the rewind reel 8 by the belt 9, the tape passing from the tape puller 5 to the reel 8 after passing under the idler or abutment 10.

Between the ticker 1 and the tape pulling roller 5, there is disposed the message translating mechanism now to be described.

It consists essentially of a platform 11 having two rows of openings or orifices 12 and 13. In order to iron out any vibrations transmitted to the tape by the ticker, there is preferably provided a lever 14 which presses the tape against a roller 15 between the ticker 1 and the platform 11. The openings 12 and 13 are preferably round and flaring outwardly in a downward direction as indicated in Fig. 8.

Preferably the openings 12 are staggered relative to the openings 13 as indicated in Fig. 7. When the tape 4 consists of two rows of printed matter as indicated in Fig. 7, which is illustrative of a piece of ticker tape in actual size about three-quarters of an inch in width, that is one-half the dimensions illustrated in Fig. 7 and in which the width of the characters in the upper row 14 are about three-sixteenths of an inch and the widest characters, to wit the fractions of the second row 15, are about one-quarter of an inch, there will be provided about six openings to each of the rows 12 and 13 in alignment with the upper row of characters 14' and about eight openings to each of the rows 12 and 13 in alignment with the second row of characters 15' as illustrated in Fig. 7.

These rows of openings 12 and 13 are provided to cooperate with the light rays produced by the lamp 16 and directed by the reflector 17

5

30

35

40

45

50

55

to pass through the condensers 18 and 19 onto the lower face of the platform 11 and then through the openings 12 and 13 onto the lower face of the tape 4, thereupon to pass through such tape 4 where the light rays are not obstructed by characters or portions of characters formed on the tape 4. In other words, the tape 4 is preferably composed of some transparent or translucent material which will readily permit the light rays to pass therethrough and the ink selected for the ticker 1 is preferably of a character that will produce a light interrupting impression on the tape 4.

Such beams as pass through the tape 4 as aforesaid will then be received by the objective lens unit mounted in the casing 20 and then diverge into independent light rays corresponding to the uninterrupted openings 12 and 13 to be received by the light sensitive mechanism consisting of the photo-electric cells 21 and 22, there being a photo-electric cell 21 for each of the openings 12 and a photo-electric cell 22 for each of the openings 13.

Consequently the photo-electric cells 21 and 22 will cooperate with the openings 12 and 13 to scan the tape 4 for light interrupting characters. The photo-electric cells 21 and 22 in the present instance are also arranged in rows which are staggered relative to one another corresponding to the staggered relation of the row of openings 12 to the row of openings 13.

There are preferably provided as many photo-electric cells 21, 22 as there are openings 12, 13, twenty-eight in the present instance.

For each photo-electric cell, there is provided an audio frequency source adapted to generate a distinct vibration or frequency so that in the present instance, there will be provided twenty-eight audio frequency devices or generators, each capable of generating its own distinct frequency. These audio frequency devices or generators are preferably as in the present instance, housed in the casing 23. Since the devices housed in the casing 23 are adapted each to generate a frequency different from one another, it is obvious that all twenty-eight frequencies may be electrically transmitted simultaneously across one and the same electric conductor, as for instance, a telephone or telegraph wire or by radio broadcast.

Furthermore, as is a specific object of the present instance that the frequencies selected may appear in the so-called inaudible ranges characterized by below sixteen vibrations per second or thirty-two thousand or more vibrations per second, it is obvious that all or a less number of the frequencies may be simultaneously transmitted across a telephone line without interfering with the use of the line for transmitting an audible message, such as by the human voice. In other words, it is here intended to cover a pulsating current whether composed of audible or inaudible frequencies selected according to the use intended.

In the present instance, each photoelectric cell is connected to an audio frequency source located in the casing 23 by means of a control tube and a transformer, each cell being connected to an individual control tube 24 by one conductor 25, which tube 24 is in turn connected by a conductor 26 with the transformer 27 and which transformer is directly connected to an audio frequency source in the casing 23 by the conductor 28. Each cell 21 is further connected to a common conductor 29 which in turn is con-

nected to the common conductor 30 which is connected to a source of current 31, which source of current 31 is connected by the conductor 32 to the conductor 33 connected to the common conductor 34 of the several audio frequency generating sources contained in the housing 23.

The transformer 27 in turn is connected to the ground or return wire by the conductor 35 and is connected by the conductor 36 to the conductor 37 in the present instance illustrative of a telephone or telegraph line.

Each of the cells 22 is similarly connected as for instance by the conductor 38 to the tube 39 and by the conductor 40 to the common conductor 29, which latter is in turn connected to the common conductor 30 as aforesaid, while the tube 39 is connected to a transformer 41 by the conductor 42, which transformer 41 is connected to its audio frequency generating source in the casing 23 by the conductor 42' and is connected to the telephone line 37 by the conductor 43.

The telephone line 37 is in turn connected to a plurality of receiving units, twenty-eight in number, each resonantly tuned to one of the 25 audio or even inaudible frequencies generated in the casing 23, which receiving units consist essentially of an audio frequency filter and amplifier housed in the present instance for convenience in the casing 44. These several 30 receiving units are in turn connected to the common ground or return wire 45.

Each of the receiving units or channels located in the casing 44 is connected to one of the electromagnets illustrated in Fig. 6. As an 35 instance, the magnet 46^a of the magnets 46 is connected by the conductor 47 to one of such receiving units and this magnet 46^a is in turn connected to a common return lead 48 to all of the receiving units by means of the conductors 49 and 50.

The adjacent magnet 46^b in the present instance is connected to its individual receiving unit by the conductor 51 and also connected to the common return lead 48 by the conductors 49 and 50. For convenience of description, the magnets in the right hand row will be designated by the reference character 46 and the magnets in the left hand row by the reference character 52. The only other conductor shown between 50 a magnet and its individual receiving unit is the conductor 53 connected to the magnet 46^a, although it is of course understood that each of the magnets 46, will be provided with an individual conductor independently connecting each 55 magnet with its individual receiving unit. The magnet 46^a in the present instance is connected to the common return lead 48 by the conductors 48^a and 48^b.

Each of the magnets 46 in the present instance 60 is operatively associated with one of the photo-electric cells 22 and each of the magnets 52 with one of the photo-electric cells 21. Each of the magnets 46 is in turn operatively associated with an impression pin 55 corresponding in position, 65 see Fig. 7, to a corresponding opening 13 in the platform 11 and each magnet 52 is in turn operatively associated with an impression pin 54 corresponding in position to a corresponding opening 12 in the platform 11.

The impression pins 54 and 55 are disposed adjacent to one another to correspond as nearly as possible to the positions of the openings 12 and 13. The free lower ends of the impression pins 54 and 55 are to be inked as hereinafter 70 75

to be described to produce impression marks corresponding to the inked impressions on the tape 4, the pins 54 reproducing such impression marks on another tape at the receiving station, to wit on the tape 56 shown in Fig. 6 on a scale. 5 of four to one as compared to full size.

In the present instance, the impression pins 54 and 55 are secured to the lower ends of the shanks 57 and 58 which are slidably mounted in the block 59. To the block 59, there is attached the container 60 constituting a reservoir for the ink 61, the base of which container is provided with openings to permit the impression pins 54 and 55 to extend therethrough to pass through a pad 62 maintained in position on the lower face of the block by the bracket 63, the pad being supplied with ink by the seepage which passes to it through the openings in the base in which the pins 54 and 55 are slidably mounted. 10

20 Beneath the bracket 63, the tape 56 is caused to pass from the supply roll 64 by the tape drawing roller 65.

In the operation of the device, when a character or letter on the tape 4 interrupts the passage of 25 light rays therethrough, this interruption will be transmitted to the receiving units there to actuate those pins 54, 55 which correspond to the openings 12, 13 which have not been obstructed. The tape 56 will be constantly advanced under the 30 bracket 63 to be at all times ready to receive an impression. The pins 54 and 55 which have been actuated will be caused to extend a short distance beyond the lower face of the bracket 63 so that if the tape as it is intended to do is pressed upwardly against such extending pin 54, 55, an impression of the same will be made. 35

It is of course understood that the ends of the pins 54, 55 may be formed to constitute round rectangular or other shaped type markings so 40 that the impression on the tape 56 may consist either of a series of dots, dashes or the like defining the areas of the letters, markings or the like to be reproduced.

In the present instance, the hammer action or 45 impression producing action will be effected by the platen 66 preferably composed of rubber or the like which is mounted on the bracket 67 and has extending from its lower face two journals 68 and 69. The journal 68 is pivotally connected to the link 70 which in turn is connected to the link 71 pivotally connected to a fixed abutment 72 at its lower end, while the pivotal connection of the links 70 and 71 with one another is pivotally connected to the link 73 which in turn is pivotally connected to the pivotal connection of the links 74 and 75 with one another. 50

The upper end of the link 74 is pivotally connected to the journal 69 and the lower end of the link 75 is pivotally connected to the fixed abutment 76. The pivotal connection of the links 74 and 75 is in turn connected by the link 77 with the counter-weighted crank 78 and the journal 69 is pivotally connected by the link 79 to the fixed abutment 80. 55

The crank 78 is preferably mounted on a shaft 81 which is drivingly connected to the shaft 82 which in turn has a bevelled gear 83 on its lower end in mesh with the bevelled gear 84 on the shaft 85. The shaft 85 is provided with a worm 60 gear 86 in mesh with the worm wheel 87 on the driven shaft 88. The speed imparted by the motor 81 to the shaft 81 through the driving connection aforesaid to the shaft 88 will be such that the tape 56 will be advanced across the platen 66 at a 65 rate substantially equal to the rate of movement

of the master at the scanning transmitter. Preferably the scanning openings 12, 13 are about one-sixty-fourth of an inch in diameter and the diameter of the impression pins 54, 55 are similarly about one-sixty-fourth of an inch. Consequently for an inch of tape, it would require at least sixty-four impressions of the pins 54, 55 to fully cover an inch of tape. So that it will not be necessary to synchronize the actuation of the platen 66 with the actuations of the pins 54, 55. 10 It is desirable to have the platen reciprocated at a speed exceeding sixty-four impressions during the movement of an inch of tape or exceeding the speed of sixty-four actuations of the impression pins 54, 55 during the passage of an inch of tape. 15 In the present instance, the driving connection from the shaft 81 to the shaft 88 is such that for the passage of an inch of the tape 56, the platen 66 will have been reciprocated into printing position at least one hundred and twenty-eight times. 20

This speed of reciprocation is desired in order to insure picking up every message that is transmitted by the actuation of the pins 54 and 55.

In order to facilitate momentary arrest of the tape 56 during the printing action, the pulling 25 roller 65 is resiliently connected to the hub or boss 89 fixed to the shaft 88, the hub 89 having a projection or ear 90 which is connected by the spring 91 with the inner face of the pulling roller 65 to urge the abutment 92 of the pulling roller 65 into 30 engagement with the projection 90. For frictionally maintaining the tape in engagement with the driving roller 65, there is provided the spring 35 pressed idler 93.

In some instances, it may be desirable to project 35 the reproduced impressions on the tape 56, in which case, see Fig. 4, the tape is caused to pass from the pulling roller 65 to and across the light aperture on the top of the extension 94 of the lamp housing 95 from which the tape 56 is drawn 40 onto the rewind reel 96 which is drivingly connected in any suitable manner of slippage compensation for changing diameter to the motor 97.

Above the light aperture in the extension 94, 45 there is provided an objective lens unit mounted in the casing 98 to receive the image impressed light rays from the light aperture of the extension 94 and direct them onto a deflector not shown and finally onto the screen 99.

The actuation of the shanks 57 and 58 and 50 thereby the pins 54, 55 by the magnets 52, 46 will now be described.

For convenience of assembly, each of the sets of magnets 46 and 52 will be divided into two rows, an inner row and an outer row. The magnets of the inner row in which the magnets 46^a and 46^b appear each has, see Fig. 5a, its core disposed in alignment with the armature 100 formed on the arm 101. The arm 101 associated with the magnet 46^a as an instance, is fixed to the rock 60 shaft 102 which in turn is provided with an arm 103, see Fig. 6, the free end of which is disposed to oscillate in a slot formed in the stop bar 104. Adjacent the stop bar 104, the arm 103 aligns with the upper end of the shank 58 in the block 59 corresponding to the photo-electric cell 22 with which the magnet 46^a is operatively connected. The shanks 57 and 58 are in turn provided with the flat springs 105 and 106 respectively for maintaining the pins 54 and 55 in raised position or 70 always in contact with arms 103, 111. In order to predetermine the extent of movement of an arm 103, 111, the stop bars 104 are provided with abutment faces 104^a to fix the extent of descent of an arm 103, 111 and thereby the extent of 75

descent of the pins 54, 55 and the stops 104^b above the arms 103, 111 determine the extent of ascent of the arms 103, 111 by their associated electromagnets. The springs 105, 106 normally urging the upper ends of the shanks 57, 58 against the arms 103, 111 in non-printing position in turn will have the extent of ascent of the arms 103, 111 fixed by the stops 104^b.

The arms 103, 111 in turn are provided with springs 107 for urging the free ends of the arms 103, 111 into pin depressing position against the tension of the weaker springs 105, 106. Each of the magnets of the outer row, as an instance, see the magnet 46^a has its core alined with the armature 108 on the free end of the arm 109 fixed to the rock shaft 110 at its lower end, which rock shaft has fixed to it an arm 111, the free end of which is similarly positioned to oscillate in the bar 104.

20 Adjacent the bar 104, the arm 111 alines with the upper end of a shank 58. This arm 111 is also provided with a spring 107 normally to urge it into pin depressing position against the tension of the weaker spring 106.

25 The operative associations of the inner and outer rows of magnets 52 with the pins 57 are substantially identical with that just described with regard to the inner and outer rows of magnets 46.

From the foregoing, it will thus appear that 30 when a character on the tape 4 interrupts the light, the interruption will be transmitted by the cells 21, 22 to corresponding magnets 46, 52 and that when so interrupted, the springs 107 will be free to depress the arms 103, 111 into pin extending position and that when so extended, the reciprocating platen 66 will immediately reproduce an impression of the extended pins onto the tape 56 thereby to reproduce the markings on the tape 4.

40 From the foregoing, it will of course also appear that markings on the tape 4 need not necessarily be produced by a printer, such as the printer 1 but can be produced by the human hand and that script when produced on the tape 4 in light interrupting ink will be reproduced on the tape 56 in the same manner.

It will of course also be obvious that instead 45 of light interrupting markings on the master 4, the master 4 may be composed of light interrupting material and provided with light passable areas, such for instance as perforations or transparency or translucency imparting impressions, in which case a negative instead of a positive picture would result without departing from the 50 general spirit of the invention.

55 In Fig. 10, there is illustrated a tape 4^a having a single row of printed matter 14^a. When tape such as the tape 4^a is used, it is of course obvious that the light openings 12, 13 can be reduced in 60 number as an instance to consist merely of the upper row of openings 12, 13 shown in Fig. 7. In this case, the audio frequency sources and related parts will of course similarly be reduced in number.

65 It is of course also obvious that the message impressed on the master may be in code form and that this message in code can in turn be translated into pulsating currents and such pulsating currents electrically transmitted and translated to actuate recording devices at the receiving stations to select characters or portions of characters corresponding to the code initially transmitted.

70 The springs 107 in the present instance effect a prompt extension of the pins 54, 55 into im-

pression creating position when the armatures 101, 108 connected thereto are released by the de-energization of the electromagnets 46, 52 operatively associated therewith.

The objective lens unit retained in the casing 5 20 cooperates with the location of the openings 12, 13 and of the photo-electric cells 21, 22 relative to one another to produce enlarged and sharply defined images of selected portions of the master tape 4, thereby to facilitate positioning the respective parts during assembly with less percentage of error and consequently facilitate control of the translation of the markings on the master tape into electrical equivalents during the process of dissecting or scanning. 15

To prevent smudging of the markings on the tape 56 at the receiving station, the bracket 63 is preferably provided with buttons 63^a at the ends thereof and disposed in alinement with those portions of the tape disposed between and to either side of the areas of the printed matter. 20

It is obvious that various changes and modifications may be made to the details of construction without departing from the general spirit 25 of the invention as set forth in the appended claims.

I claim:

1. The system of transmitting messages consisting of a transmitting station having a record 30 or master composed of a light transmittable tape having light interrupting characters impressed thereon, a pulsating current generator for generating a plurality of pulsating currents corresponding to the location of light rays transmitted through said tape, a light sensitive mechanism operatively associated with said pulsating current generator, a source of light for directing the light rays through the unimpressed portion of said record and onto said light sensitive mechanism in turn to select the pulsating currents corresponding to the light rays being transmitted, and a receiving station having a pulsating current filter means for filtering out a plurality of pulsating currents corresponding to the frequencies of said transmitting station, a mechanical recording device, and means operatively associating said mechanical recording device with said pulsating current filter means electrically to control said mechanical recording device in accordance with the pulsating currents transmitted to record the message transmitted. 40

2. In a message transmitting system, the combination with a transmitting station having a master and means for impressing a message on the surface of said master, of a receiving station having a tape, a recording device for mechanically recording a message on said tape, a generator for translating the message on said master into pulsating currents, devices for electrically transmitting said pulsating currents to said receiving station, a separator at said receiving station for separating said pulsating currents, and an electrical controller operatively associated with said mechanical recording means electrically to control 55 said recording means to record on said tape the message transmitted. 60

3. In a message transmitting system, the combination with a transmitting station having a master and means for impressing a message on the surface of said master, of a receiving station having a tape and means for recording a message on the surface of said tape, means for translating the message on said master into audio frequencies, means for electrically transmitting said 70 75

audio frequencies to said receiving station, and means including magnets operatively associating said transmitting means with said recording means to record on said tape the message transmitted.

4. In a message transmitting system, the combination with a transmitting station having a master and means for impressing a message on the surface of said master, of a receiving station having a tape and means for recording a message on said tape, means including a light sensitive mechanism for translating the message on said master into audio frequencies, means for electrically transmitting said audio frequencies to said receiving station, and means including magnets operatively associating said transmitting means with said recording means to record on said tape the message transmitted.

5. In a message transmitting system, the combination with a transmitting station having a master and means for impressing a message on the surface of said master, of a receiving station having a tape and means for recording a message on said tape, means including a light sensitive mechanism for translating the message on said master into audio frequencies, means for electrically transmitting said audio frequencies to said receiving station, and means including an audio frequency filter operatively associating said transmitting means with said recording means to record on said tape the message transmitted.

6. In a message transmitting system, the combination with a transmitting station having a light transmittable master and means for impressing a message on said master in light interrupting characters, of a receiving station having a tape and means for recording a message on said tape, an audio frequency generator, a light sensitive mechanism operatively associated with said audio frequency generator, a source of light operatively associated with said master for directing light rays through the unimpressed portion of said tape onto said light sensitive mechanism in turn to cause the selection of generated audio frequencies corresponding to the message impressed, means including an audio frequency filter for transmitting the audio frequencies selected to said receiving station, and means including magnets operatively associating said audio frequency filter with said recording means to record on said tape the message transmitted.

7. In a message transmitting system, the combination with a transmitting station having a light transmittable master and means for impressing a message on said master in light interrupting characters, of a receiving station having a tape and a device for recording a message on said tape, an audio frequency generator, a light sensitive mechanism operatively associated with said audio frequency generator, a source of light operatively associated with said master for directing light rays through the unimpressed portion of said tape onto said light sensitive mechanism in turn to cause the selection of generated audio frequencies corresponding to the section of the message impressed, means including an audio frequency filter for transmitting the audio frequencies generated to said receiving station, and means including magnets operatively associating said audio frequency filter with said recording devices to make inoperative those recording devices which correspond to the section of the message transmitted whereby the message will be recorded by the recording devices not so made inoperative.

8. In a message transmitting system, the combination with a light transmittable master, of means for impressing light interrupting markings on said master, a stationary platform having a plurality of openings, a light sensitive mechanism having a plurality of devices each corresponding to one of said openings, means for drawing said master across said platform, a source of light for directing light rays through the openings in said platform not obstructed by light interrupting markings onto corresponding devices, and an audio frequency generator having devices for generating a plurality of frequencies corresponding to the number of openings in said platform, each device of said generator being operatively associated with one of the devices of said light sensitive mechanism to select the frequency corresponding to its associated unobstructed opening.

9. In a message transmitting system, the combination with a light transmittable tape, of a printer for impressing a message in light interrupting areas on said tape, a stationary platform having a row of openings, a plurality of light sensitive devices one corresponding to each of such openings, means for drawing said tape across said row of openings, a source of light for directing light rays through the openings in said platform not obstructed by light interrupting areas onto corresponding light sensitive devices, and an audio frequency generator having devices for generating a plurality of different frequencies corresponding to the number of openings in said platform, each device of said generator being operatively associated with one of said light sensitive devices to control the frequency corresponding to its associated unobstructed opening.

10. In a message transmitting system, the combination with a light transmittable tape, of a printer for impressing a message in light interrupting markings on said tape, a stationary platform having a plurality of rows of openings, a plurality of light sensitive devices, one corresponding to each of such openings, means for drawing said tape transversely across said rows of openings, a source of light for directing light rays through the openings in said platform not obstructed by light interrupting markings onto corresponding light sensitive devices, an audio frequency generator having devices for generating a plurality of different frequencies corresponding to the number of openings in said platform, each device of said generator being operatively associated with one of said light sensitive devices to control the frequency corresponding to its associated unobstructed opening, and a receiving station having a recorder operatively associated with said generator to reproduce the message formed on said tape.

11. In a message transmitting system, the combination with a transmitting station having a generator for generating a plurality of audio frequencies corresponding to the section of markings on a tape, of a receiving station having an audio frequency filter operatively associated with said generator, a plurality of printing bars, means for yieldably maintaining said bars in extended impression creating position, means including a plurality of magnets, one for each printing bar operatively associated with said audio frequency filter for withdrawing the printing bars corresponding to the audio frequencies selected to leave extended these printing bars corresponding to the markings on the tape at the transmitting station, a platen, means for drawing a second

tape across said platen adjacent to said printing bars, and means for reciprocating said platen into impression receiving contact with said printing bars.

- 5 12. In a message transmitting system, the combination with a transmitting station having a generator for generating a plurality of audio frequencies corresponding to the section of markings constituting a message, of a receiving station having an audio frequency filter, said filter having a resonantly tuned device forming a channel corresponding to each of the audio frequencies generated by said generator, a plurality of printing bars, means for yieldably maintaining said bars in 10 extended printing position, means operatively associating each of said bars with one of said filtering devices for withdrawing the printing bars corresponding to the audio frequencies generated and leave extended those printing bars corresponding 15 to the markings constituting the message, a platen, means for drawing the tape across said platen adjacent to said printing bars, and means for reciprocating said platen into impression receiving contact with said printing bars.
- 20 13. In a message transmitting system, the combination with a transmitting station having a generator for generating a plurality of audio frequencies corresponding to a succession of points constituting the sections of characters, of a receiving station having an audio frequency filter, said filter having a plurality of filtering devices each corresponding to one of the audio frequencies generated, a plurality of point producing printing bars, a block in which said printing bars 25 are vertically slidable, an ink reservoir associated with said block, means for yieldably maintaining said bars in depressed impression creating position, means operatively associated with said filtering devices for withdrawing the printing bars 30 corresponding to the audio frequencies generated, a platen, means for drawing a tape between said platen and said printing bars, and means for reciprocating said platen into impression receiving contact with said printing bars at a rate 35 per unit of time corresponding to a number per unit of time exceeding the number of impression areas required to cover a unit length of tape per unit of time.
- 40 14. In a message transmitting system, the combination with a master, of means for impressing light interrupting markings on said master, a platform having a plurality of openings, a light sensitive mechanism having a plurality of devices each corresponding to one of said openings, means 45 for drawing said master across said platform, a source of light for directing light rays through the openings in said platform not obstructed by light interrupting markings onto corresponding devices, an audio frequency generator for generating a plurality of frequencies corresponding to the number of openings in said platform, said generator being operatively associated with said light sensitive mechanism to select the frequencies 50 corresponding to unobstructed openings, a receiving station having an audio frequency filter, said filter having a plurality of filtering devices, one corresponding to each frequency generated by said generator, a plurality of printing bars, 55 means for yieldably maintaining said bars in extended impression creating position, means operatively associated with said filtering devices for withdrawing the printing bars corresponding to the audio frequencies generated, a platen, 60 means for drawing a tape across said platen, and 65 70 75 means for drawing a tape across said platen, and

means for reciprocating said platen into impression receiving contact with said printing bars.

15. In a message transmitting system, the combination with a transmitting station having a master and means for impressing a message on said master in light interrupting characters, of a receiving station having a tape and a device for recording a message on said tape, a pulsating current generator for generating inaudible frequencies, a light sensitive mechanism operatively associated with said pulsating current generator, a source of light operatively associated with said master for directing light rays through the unimpressed portion of said tape onto said light sensitive mechanism in turn to select and control said generated inaudible frequencies corresponding to the message impressed, means including a wire for electrically transmitting said inaudible frequencies to said receiving station without interfering with the use of said wire for carrying the normal audible voice currents, and means including an inaudible frequency filter operatively associating said wire with said recording device to record on said tape the message transmitted.

16. In a message transmitting system, the combination with a transmitting station having a light transmittable master and means for impressing a message on said master in light interrupting characters, of a receiving station having a tape and a device for mechanically recording a message on said tape, an audio frequency generator, a light sensitive mechanism at the transmitting station operatively associated with said audio frequency generator, a source of light operatively associated with said master for directing light rays through the unimpressed portion of said tape onto said light sensitive mechanism in turn to select and control the flow of generated audio frequencies corresponding to the message impressed, means including a channel for electrically transmitting said audio frequencies to said receiving station, and means including an audio frequency filter means operatively associating said channel with said recording device for electrically controlling said recording device mechanically to record on said tape the message transmitted.

17. In a message transmitting system, the combination with a master, of means for impressing light interrupting markings on said master, a platform having a row of openings, a light sensitive mechanism having a plurality of devices, each corresponding to one of said openings, means for drawing said master longitudinally across said row of openings, a source of light for directing light rays through openings in said platform not obstructed by light interrupting markings onto corresponding devices, an audio frequency generator for generating a plurality of frequencies corresponding to the number of openings in said platform, said generator being operatively associated with said light sensitive mechanism to select and control the frequencies corresponding to unobstructed openings, a receiving station having an audio frequency filter, said filter having a plurality of filtering devices, one corresponding to each frequency generated by said generator, a row of printing bars corresponding in number and position to the openings in said platform, means for yieldably maintaining said bars in extended impression creating position, means operatively associated with said filtering devices for withdrawing the printing bars corresponding to the audio frequencies selected, a

platens, means for drawing a tape longitudinally across said row of bars in the same direction that the master is drawn across said openings, and means for reciprocating said platen into impression receiving contact with said printing bars.

18. In a message transmitting system, the combination with a transmitting station having a generator for generating a plurality of audio frequencies corresponding to the area of markings on a tape, of a receiving station having an audio frequency filter operatively associated with said generator, a plurality of printing bars, means for yieldably maintaining said bars in extended impression creating position, means including a plurality of magnets, one for each printing bar operatively associated with said audio frequency filter for withdrawing the printing bars corresponding to the audio frequencies selected to leave extended those printing bars corresponding to the markings on the tape at the printing station, a platen, a tape puller for actuating said tape puller continuously to draw a second tape across said printing bars, actuating means for said tape puller, means for yieldably connecting said tape puller to said actuating means in order to compensate for any retarding action imparted to the tape during the printing action, and means for reciprocating said platen into impression receiving contact with said printing bars.

19. In a message transmitting system, the combination with a transmitting station having a generator for generating a plurality of audio frequencies corresponding to the areas of markings on a tape, of a receiving station having an audio frequency filter operatively associated with said generator, a plurality of printing bars, means for yieldably maintaining said bars in extended impression creating position, means including a plurality of magnets, one for each printing bar operatively associated with said audio frequency filter for withdrawing the printing bars corresponding to the audio frequencies selected to leave extended those printing bars corresponding to the markings on the tape at the transmitting station, a platen, means for drawing at a uniform rate of speed a second tape across said platen adjacent to said printing bars, means for reciprocating said platen into impression receiving contact with said printing bars, an inspection area and a second tape drawing means for drawing said second tape across said inspection area, said first drawing means being disposed in advance of said inspection area to cooperate with said second drawing means to maintain the tape smooth while crossing said inspection area without any auxiliary control.

20. In a message transmitting system, the combination with a transmitting system having a master and means for impressing a message on said master in light interrupting characters, a platform having two rows of openings, a plurality of light sensitive devices, one corresponding to each of said openings, means for drawing said tape longitudinally across said rows of openings, a source of light for directing light rays through the openings in said platform not obstructed by light interrupting markings onto corresponding light sensitive devices, an audio frequency generator for generating a plurality of different frequencies corresponding to the number of openings in said platform, said generator being operatively associated with said light sensitive devices to generate the frequencies corresponding to the unobstructed openings, a receiving station having an audio frequency filter, said filter having a plu-

rality of filtering devices, one corresponding to each frequency generated by said generator, two rows of printing bars each corresponding in position and location to one of said openings, means for yieldably maintaining said bars in extended impression creating position, means operatively associated with said filtering device for withdrawing the printing bars corresponding to the audio frequencies selected, a platen, means for drawing a tape across said platen, and means for reciprocating said platen into impression receiving contact with said printing bars.

21. A receiving station for a message transmitting system having an audio frequency filter, a plurality of printing bars, means for yieldably maintaining said bars in extended impression creating position, means including a plurality of magnets, one for each printing bar operatively associated with said audio frequency filter for withdrawing the printing bars corresponding to the audio frequencies selected to leave extended those printing bars corresponding to the marks to be produced, a platen, means for drawing a tape across said platen adjacent to said printing bars, and means for reciprocating said platen into impression receiving contact with said printing bars.

22. A receiving station for a message transmitting system having an audio frequency filter, said filter having a resonantly tuned device forming a channel corresponding to each of the audio frequencies generated, a plurality of printing bars, means for yieldably maintaining said bars in extended printing position, means operatively associating each of said bars with one of said filtering devices for withdrawing the printing bars corresponding to the audio frequencies generated and leave extended those printing bars corresponding to the marks to be produced, a platen, means for drawing the tape across said platen adjacent to said printing bars, and means for reciprocating said platen into impression receiving contact with said printing bars.

23. A receiving station for a message transmitting system having an audio frequency filter, said filter having a plurality of filtering devices each corresponding to one of the audio frequencies generated, a plurality of point producing printing bars, a block in which said printing bars are vertically slidably, an ink reservoir associated with said block, means for yieldably maintaining said bars in depressed impression creating position, means operatively associated with said filtering devices for withdrawing the printing bars corresponding to the audio frequencies generated, a platen, means for drawing a tape between said platen and said printing bars, and means for reciprocating said platen into impression receiving contact with said printing bars at a rate per unit of time corresponding to a number per unit of time exceeding the number of impression areas required to cover a unit length of tape per unit of time.

24. A receiving station for a message transmitting system having a printer, said printer having a plurality of printing bars, means for yieldably maintaining said bars in extended impression creating position, means including a plurality of magnets for controlling the actuation of said printing bars, a platen, means for continuously drawing a tape across said platen adjacent to said printing bars, means for continuously reciprocating said platen into impression receiving contact with said printing bars while said tape is being fed by said tape drawing means, actuating

means operatively associated with said reciprocating means, means for yieldably connecting said tape drawing means to said actuating means in order to compensate for any retarding action imparted to the tape during the printing action, an inspection area, a second tape drawing means for drawing said tape across said inspection area, a continuously operating motor, and a slippage device for operatively connecting said second tape drawing means with said motor to compensate for any variation in speed imparted to the tape by said yieldable means.

25. The system of transmitting messages consisting of a transmitting station having a record or master composed of a light transmittable tape having light interrupting characters impressed thereon, a pulsating current generator for generating a plurality of pulsating currents corresponding to the location of light rays transmitted through said tape, means operatively associating said pulsating current generator and said light transmittable tape to select the pulsating currents required to define the message to be transmitted, and a receiving station having a pulsating

current filter means for filtering out a plurality of pulsating currents corresponding to the frequencies of said transmitting station, a mechanical recording device, and means operatively associating said mechanical recording device with said current filter means electrically to control said mechanical recording device in accordance with the pulsating currents transmitted to record the message transmitted.

26. In a message transmitting system, the combination with a transmitting station having a master and means for impressing a message on the surface of said master, of a receiving station having a tape and means for recording a message on said tape, means including a light sensitive mechanism for translating the message on said master into audio frequencies, means for electrically transmitting said audio frequencies to said receiving station, and means operatively associating said transmitting means with said recording means to record on said tape the message transmitted.

AUGUST D. EITZEN.
